(57) CLAIM

What is claimed is the ornamental design for a sandal, as shown and described.

DESCRIPTION

FIG. 1 is a perspective view of sandal, showing the new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left-side elevational view thereof; and,

FIG. 7 is a right-side elevational view thereof.

The broken lines showing a foot in FIG. 1 and a sandal sole in FIGS. 1-7 are included for the purpose of illustrating the invention in use, and form no part of the claimed design.
